UNITED STATES PATENT OFFICE.

CHARLES JOHNSON, OF PEORIA, ILLINOIS.

WALL-PIPE FOR FURNACES.

1,164,354.

Specification of Letters Patent. Patented Dec. 14, 1915.

Application filed October 13, 1914. Serial No. 866,531.

To all whom it may concern:

Be it known that I, CHARLES JOHNSON, a citizen of the United States, residing at Peoria, in the county of Peoria and State 5 of Illinois, have invented certain new and useful Improvements in Wall-Pipes for Furnaces; and I do hereby declare the following to be a full, clear, and exact description of the invention, such as will enable 10 others skilled in the art to which it appertains to make and use the same.

This invention relates to wall pipes for furnaces, and one of the principal objects of the invention is to provide a rectangular 15 wall pipe section comprising two members, an inner member and an outer member connected together and provided with braces and openings which will give a free circulation between the inner and outer walls and 20 said sections each being provided with a reduced end and a larger end to fit the next adjacent section, said pipe sections each being formed of two pieces properly seamed and connected together.

25 The foregoing and other objects may be attained by means of the construction illustrated in the accompanying drawing, in which,

Figure 1 is a perspective view of one of 30 the pipe sections, Fig. 2 is a longitudinal sectional view of the same, Fig. 3 is a vertical section taken through two sections connected together. Fig. 4 is a detail sectional view showing the method of double seaming 35 the ends of the inner and outer walls together.

Referring to the drawing, the numeral 1 designates the inner member and 2 is the outer member of the section, said members 40 being preferably formed of tin or other sheet metal of the required thickness, and said outer member being provided with openings 3 formed in the inclined portion 4, and said openings being formed by cutting 45 tongues or braces 5 out of the material and bending said braces inwardly to bear against the inner member 1 of the pipe sections. The inner section 1 at its upper end is bent over the outer section to form an

inclosing flange 6 adapted to hold the two 50 members together firmly. The inner member 1 is provided with an inclined portion 7, having openings 8 therein and tongues cut from the inclined portion 7, said tongues 9 forming braces against the outer member 55 of the wall 2. The outer member 2 is flanged over the lower edge of the member 1 as shown at 10.

From the foregoing it will be obvious that one section will fit smoothly over the other 60 and not leave a projection either on the inner or outer side of the pipe, and that there is a good clear space between the inner and outer members of each section, and that they are braced by the tongues 5 to give 65 stability to the pipe section.

Various changes may be made in the details of construction without departing from the spirit and scope of the invention as defined in the claim. 70

What is claimed is:—

A wall pipe for furnaces comprising a plurality of sections, each section comprising an inner and outer wall, said outer wall being inclined inwardly at its upper edge 75 toward the inner wall, said inner wall being inclined outwardly toward the outer wall, whereby said sections are fitted one to the other, the walls of said sections being oppositely flanged to secure them together, 80 said outer wall having tongues cut out from the inclined portion below the flange, the inner wall having similar tongues cut out from the inclined portion above the flange, 85 said tongues being bent inwardly, whereby said walls are held in spaced relation, the apertures thus formed being adapted to register with similarly formed apertures in the other section when said sections are fitted together, whereby air can circulate through 90 the sections, and the tongues serving to spread the air.

In testimony whereof I affix my signature in presence of two witnesses.

CHARLES JOHNSON.
